UNITED STATES PATENT OFFICE.

CHARLES A. POOLE, OF JERSEY CITY, NEW JERSEY.

TILTALBE POST.

1,269,212.

Specification of Letters Patent. Patented June 11, 1918.

Application filed April 19, 1916. Serial No. 92,106.

To all whom it may concern:

Be it known that I, CHARLES A. POOLE, of Jersey City, Hudson county, New Jersey, a citizen of the United States, have invented 5 certain new and useful Improvements in Tilttable Posts, of which the following is a specification.

This invention relates to improvements in tilttable posts adapted for use as signal or 10 lamp posts and the object of the invention is to provide a post having freedom of movement in all directions, so that when struck, by a vehicle for instance, or from other cause, the post will be tilted instead of 15 breaking or bending, and automatically return to vertical position. In cases where the post serves as a sign post, in addition to carrying lighting fixtures, the invention contemplates the provision of means for preventing lateral displacement of that portion 20 of the post which carries streets signs or the like.

With the above and other objects in view, my invention is embodied in a tilttable post 25 as hereinafter described and as illustrated in the accompanying drawing in which—

Figure 1 is a vertical sectional view of the post with parts broken away;

Fig. 2 is a plan view of the foundation 30 member with the base of the post tilted and shown in section.

Fig. 3 is an enlarged sectional view of a portion of the foundation member and the post base showing the means for preventing 35 lateral displacement of the latter, and

Fig. 4 is a view in elevation of the parts shown in Fig. 3.

The reference numeral 5 denotes a foundation member adapted to be buried in the 40 ground flush with the street surface 6 and provided with a retaining flange 7 and lugs 8, which preferably project inwardly and are adapted to receive the foundation bolts 9 which are screwed into a concrete foundation 45 10 which is carried up over the retaining flange 7 to the street surface and whereby the foundation is firmly anchored. Above the street surface the foundation member is formed with a collar 11 having

lugs 12 to which a cross bar 13 may be bolted 50 as shown. To said cross bar 13 is secured a pipe 14 by means of coupling members at 15. The pipe 14 is also extended down into the concrete in which a suitable opening is provided, as shown, for connection with the 55 electric service cable 16 or gas supply pipe if such is used. 17 is a wire cable extending down into the pipe 14 and which carries a piston 18 at its lower end, which piston is packed in the usual manner to move substantially airtight in the pipe 14 which forms a cylinder for the said piston. 60 is an air pipe connected to the pipe 14 by a branch 61. The air pipe 60 carries at the top a check valve 62 and an air regulating 65 valve 63 which may be adjusted by tilting the post. 19 is an expansion spring urging the piston 18 downward, hence exercises a constant downward pull on the cable 17.

The post comprises the post member 20, 70 the base member 21 and the lamp or sign device 22 which in this instance carries certain street names as shown. The post member 20 is preferably a pipe screwed into the base and secured against lateral displacement with respect thereto by any suitable means as the pin 23 for instance. The lamp carries the electric bulb 24 to which current is supplied by a suitable cable 25 connected to the service mains 16 and which extends 80 up through the pipe 20. The concrete foundation is hollowed out as shown to provide space for the slack of the cable and to facilitate inspection and repairs.

The base 21 is relatively heavy and in the 85 form of an inverted cup designed to closely hug the base collar 11 with just sufficient freedom of movement to permit the base 21 to tilt. 27 is a cross bar secured to the base. The wire cable 17 extends up through the 90 said bar and is knotted or provided with means for exerting a steady downward pull on the base and post under the influence of the spring 19 as is obvious.

At the foot of the collar 11 on the foundation member 5 there is provided a horizontal shoulder 28 as shown. The foundation member is provided with teeth, lugs or

projections 30 in the corner between the collar 11 and the seat 28 formed by said shoulder, Fig. 3. The projections are carefully shaped with vertical sides 31 and rounded corners 32. The base 21 is provided with a corresponding number of sockets or hollowed out portions 33 of a shape to permit the base to tilt and at the same time insure that the teeth or portions 34 on the base remain at all times seated in the spaces 35, Fig. 2, between the teeth 30 on the foundation member. Grooves as 45 may be provided to carry off the water. As clearly shown in Fig. 3, the sockets 33 of the base have inwardly sloping roofs or bottoms 36, the inner arch 37 or opening of which fits closely over the tooth 30 while the outer arch 38 or opening is of a height equal to the length of the tooth 30 to permit the base to tilt and whereby as shown in Fig. 3 at 40, when the base has been tilted into extreme horizontal position, the teeth 34 remain on their seats 35 on the foundation.

The object of this construction is to prevent the base from "climbing" the foundation when the post is tilted which would cause it to become laterally displaced on the foundation before coming to rest in the vertical position and whereby the signs on the post would become displaced and useless.

Experiments have demonstrated that when the post is tilted by a violent blow, it gyrates on the foundation in trying to right itself. In so doing it is apt to move laterally on the foundation. The means described, however, prevents such lateral displacement. It will be noted that in the half-way down position at 50 in Fig. 3, a large portion of the tooth 34 remains between the teeth on the foundation, and the vertical sides 31 on the sockets 33 coöperate with the vertical sides 31 on the teeth 30 to prevent the teeth on the base from "jumping" the teeth on the foundation.

When the post tilts the piston 18 is pulled up in the pipe 14 and sucks air into the latter by way of the check valve 62 and the pipes 60 and 61. When the post is pulled back into vertical position, the piston 18 is pushed down into the pipe 14 and as now the check valve is closed, the air below the piston is compressed into a cushion for checking the violence of the come back motion of the post, and the latter will, instead of swaying considerably back and forth for a while, almost immediately come to rest on the foundation member. The valve 63 may be adjusted so as to provide for a more or less rapid exit of the air from the pipe 14 as is obvious.

From the foregoing read together with the drawing it is apparent that the post is kept normally upright because of its weight and the pull of the spring on the cable 17. When

a vehicle strikes the base only, the wheels will glide off from it because of the cup 65 shape. And when the blow is strong enough, the post will be tilted, but pulled upright again by the spring and the cable.

The tilttable post as herein described and illustrated is very simple in construction, 70 easy to erect and may be manufactured at a reasonably low figure. I do not, of course, intend to limit myself by using the terms teeth or sockets or by describing or showing these or other parts in their preferred form. 75 But I intend to claim all such modifications of constructions as come within the scope of the principle of my invention and the appended claims.

I claim:—

1. A tilttable post comprising a foundation member, a post member resting on the same and adapted to tilt thereon, directing means on said post, projections formed on said foundation member, coöoperating projections formed on said post member and adapted to fit between the projections on the foundation member, flexible means connecting the said two members and means tending to maintain said post member in normally up- 90 right position.

2. A tilttable post comprising a foundation member, a post member thereon and adapted to tilt with respect thereto, directing means on said post, coöoperating means on said members preventing relative lateral displacement of the same and means for checking the return movement of said post after it has been tilted.

3. A tilttable post comprising a foundation member, a post member directing means on said post adapted to tilt on said foundation member, projections formed on one of said members, the other of which is provided with corresponding recesses adapted to fit 105 over the said projections, means tending to maintain said post in normal vertical position and means for checking the return movement of said post after it has been tilted.

4. A tilttable post comprising a foundation member having an upwardly projecting portion, a post member supported on said foundation member and adapted to tilt with respect thereto, directing means on said post, 115 said post member being provided with a cup shaped base adapted to surround and closely hug said upwardly projecting portion on the foundation member, means tending to maintain the said post in upright position and 120 means for checking the return movement of said post after it has been tilted.

5. A tilttable post comprising a foundation member, a post member thereon and adapted to tilt with respect thereto, directing means 125 on said post, means tending to maintain said

post member in upright position and means for checking the return movement of the post after it has been tilted.

6. A tilttable post comprising a foundation member, a post member thereon and adapted to tilt with respect thereto, directing means on said post, flexible means connecting the said two members, a piston attached to said

flexible means, a cylinder within which said piston moves, means for admitting air to the cylinder below the said piston when the post is tilted, means for restoring the post to upright position and means for regulating the escape of the air in the cylinder when the said post again assumes its upright position. 15

CHARLES A. POOLE.
